UNITED STATES PATENT OFFICE.

OTTO C. BRITSCH, OF WOODHAVEN, NEW YORK, ASSIGNOR TO HENRY HYMAN, OF BROOKLYN, NEW YORK.

COMBINATION RESISTANCE AND REFLECTOR UNITS.

Application filed April 23, 1926. Serial No. 104,050.

My invention relates to combination resistance and reflector units, particularly suitable for and preferably used in connection with electrical lighting devices for Christmas trees.

As Christmas tree lights are usually installed there are eight lights in series on a string. Should one of these lamps burn out the circuit of all the others is open and they also go out.

I have overcome this difficulty by connecting a resistance in shunt with each lamp so that if the lamp filament burns out, the circuit for the other lamps is maintained. I prefer to mount the resistance on a reflector and connect it so that when the reflector is in position, the resistance will be automatically connected in shunt to the lamp.

My invention will be better understood by reading the following description taken in connection with the accompanying drawings, in which—

Fig. 1 is a vertical section of a reflector showing the arrangement of the parts;

Fig. 2 is a diagrammatic view of certain parts of the unit;

Fig. 3 is an elevation of a portion of the resistance unit;

Fig. 4 is an elevation of a modified form of the unit;

Fig. 5 is a vertical section of the device shown in Fig. 4;

Fig. 6 is a circuit diagram of a string, or outfit; and

Fig. 7 is a circuit diagram of a modified form of the invention.

The unit consists of a base 1 of porcelain or other insulating material having a screw-threaded member thereon. The member 2 may be extended and somewhat enlarged to form the socket 3. The reflector 4 forming the body of the device may be of any suitable material, although I prefer to make it of asbestos composition, which is not only an insulating material but fireproof as well. Preferably in the perimeter of the reflector the resistance unit 5 is imbedded on a core 6 of any suitable material.

Extending through the porcelain base 1 is a screw 7 having a head 8 which engages the center contact of the usual lamp socket. The other end of the screw 7 extends into the socket 3 and connects with a metal strip 9, which in turn connects with the resistance 5. The other end of the resistance 5

connects with a strip 10, which in turn is connected to the socket 3. The end 11 of the screw 7 forms the center contact of the socket and when the lamp is screwed into the socket 3 the center contact engages the end 60 11, thus connecting one end of the filament to the circuit, and the shell of the lamp base engages the socket 3, thus connecting the other end of the filament to the circuit and at the same time the resistance 5 is connected in shunt with the filament. The surface 12 of the reflector may be of any desirable character, either plain, polished or colored, so as to produce the desired effect as a decoration.

The form of the invention shown in Figs. 4 and 5 is fundamentally the same as that shown in Figs. 1 to 3, but the reflector is divided into two parts 13 and 14. These parts are preferably of porcelain and the part 13 75 is molded around the shell 15 and holds the screw 16 in position, as shown in Fig. 5. One end of the resistance 17 is connected with the shell 15 by a conductor 18, and the other end is connected with the screw 16 by a conductor 19. The member 14 of the reflector is provided on its interior with screw threads and may be screwed into place on the socket 20, as shown in Figs. 4 and 5. Openings 21 are provided in the members 13 and 14 so 80 as to allow free circulation of air around the resistance to keep its temperature down. By reference to Figs. 4 and 5, it will be noted that a substantial part of the resistance 17 is exposed to the air.

In Fig. 6, I have shown a circuit diagram in which the resistances 5 are connected in shunt with the lamp filament A. From this diagram it will be plain that upon the burning out of one or more filaments, the circuit 95 of the other filaments will be maintained through the resistances 5.

In Fig. 7, I have illustrated a modified form of the invention wherein a second resistance 22 is connected in multiple with a 100 part of the resistance 23. The resistance 22 may be a lamp filament, a cigar lighter, or any other device. The advantage of connecting the resistance 22 at intermediate points of the resistance 23 is that usually one side 105 of the domestic lighting circuit is grounded, as, for instance, the negative where D. C. current is used. In the arrangement shown in Fig. 7, if the end 24 of resistance 22 should become grounded as by touching a radiator 110

or other device, the resistance 25 would be across the circuit. That is to say, current would flow from the plus wire 26 to ground at the point 24 through resistance 25. Under 5 like circumstances, if the point 24 were connected directly to the conductor 26 as at 27, a ground on the point 24 would result in a dead short circuit across the wires 26 and 28. In the event that the wires 26 and 28 were 10 supplied by A. C. current, either side of the resistance 22 might be grounded without causing a short circuit.

The devices shown in the drawings may be used for other purposes than reflectors, for 15 instance, as units in an electric heater. In such case a plurality of the units are screwed together to form the desired size of heater.

Many advantages of my device will be apparent to those skilled in the art and many 20 changes may be made in details without departing from the spirit of my invention.

I claim:

1. A reflector for Christmas tree lights having an upper member carrying a screw

25 plug and a socket, a resistance unit having one end connected to the center contact of the plug and the other to the socket and a lower member for said reflector adapted to be screwed onto said socket to hold the said resistance between said upper and lower members.

2. In combination, a body having a socket 30 therein for the reception of an electrical power consumption device, two contacts in said socket and adapted to be connected when said device is inserted in the socket, and a fixed resistance in the form of a continuous conductor substantially embedded in said body and having its ends permanently connected to said contacts, thereby forming a 35 shunt circuit of fixed resistance in parallel with the lamp whereby when the device is in place in the socket, a circuit therethrough is normally established and whereby when the circuit through said device is interrupted a 40 shunt circuit through the resistance is provided.

OTTO C. BRITSCH.
